DESIGN FOR A PIN-UP LAMP

Joseph W. Solomon, Bronx, N. Y., assignor to
The Verplex Company, Essex, Conn., a corporation of Connecticut

Application December 22, 1943, Serial No. 112,070

Term of patent 7 years

(Cl. D48—23)

To all whom it may concern:

Be it known that I, Joseph W. Solomon, a citizen of the United States, residing at Bronx, Bronx County, New York, have invented a new, original and ornamental Design for a Pin-Up Lamp, of which the following is a specification, reference being had to the accompanying drawing, forming part thereof.

Fig. 1 is a side elevational view, partly in section of a pin-up lamp showing my new design;

Fig. 2 is a front view of the disc portion and the ornamental figure of the lamp substantially on the line 2—2 of Fig. 1.

I claim:

The ornamental design for a pin-up lamp, substantially as shown.

JOSEPH W. SOLOMON.
